TWO-STROKE INTERNAL COMBUSTION
ENGINE

Hans Heinzelmann, Winterthur, Switzerland, assignor to the firm of Sulzer Frères Société Anonyme, Winterthur, Switzerland

Application December 4, 1930, Serial No. 499,933,
and in Switzerland December 18, 1929

1 Claim. (Cl. 123—65)

This invention relates to two-stroke internal combustion engines of the kind having two admission ports or sets of admission ports so arranged as to be successively uncovered by the 5 piston during the expansion stroke.

In two-stroke internal combustion engines in which the scavenging of the cylinder is effected through sets of admission ports which are successively uncovered by the piston, it has been proposed to form the set of ports last covered by the piston during the compression stroke so that the charge issues therethrough substantially tangentially. With such an arrangement, however, the cross-sectional area of the inlets from the ports is 15 undesirably reduced owing to the tangential arrangement of these ports with the result that the scavenging air has to be forced into the cylinder at such high velocity as to result in an incomplete scavenging on account of this air becoming undesirably mixed with the combustion products.

In a two-stroke internal combustion engine according to the present invention the admission ports extend over a greater part of the circumference of the cylinder than the exhaust ports and 25 are adapted to be successively uncovered by the piston, whereby the admission ports last closed by the piston during the compression stroke are arranged tangentially with respect to a circle substantially concentric with the cylinder axis, 30 while the admission ports first close by the piston during the compression stroke open into the cylinder substantially radially so as to obtain rapid scavenging of the cylinder when the piston is at its lower dead centre and to impart a whirling motion to the air remaining in the cylinder after scavenging.

Three alternative constructions according to the invention are diagrammatically illustrated in the accompanying drawing, in which

Figures 1, 2 and 3 respectively show the three alternative constructions in sectional elevation,

Figure 4 is a section in the plane IV—IV of Figure 1,

Figure 5 is a section in the plane V—V of Figure 1,

Figure 6 is a partial section in the plane VI—VI of Figure 2,

Figure 7 is a corresponding section to Figure 50 6 in the plane VII—VII of Figure 2,

Figure 8 is a partial section in the plane VIII—VIII of Figure 3, and

Figure 9 is a partial section in the plane IX—IX of Figure 3.

55 In each of the constructions shown the engine

comprises a cylinder 1 having a working chamber 2 the upper end of which is closed by a cylinder head or cover 3. Disposed within the cylinder is a piston 4 adapted to uncover at the end of its expansion stroke two sets of admission ports, the 60 lower set comprising ports 5 situated opposite to exhaust ports 6, and ports 7 arranged between the ports 5 and the ports 6, while the upper set comprises ports 9 situated opposite to the exhaust ports 6 and ports 10 disposed between the 65 ports 9 and the ports 6. The supply of air to the ports 5 and 7 can take place freely while that to the ports 9 and 10 is controlled by one or more valves 8. It will be seen that the admission ports occupy a larger proportion of the circumference 70 of the cylinder than the exhaust ports.

In each of the constructions shown the lower series of admission ports are disposed relatively to the exhaust ports so that they will be closed on the compression stroke before the exhaust 75 ports are completely closed. On the other hand, some at least of the upper set of admission ports extend above the exhaust ports so that they are maintained open during the compression stroke after the exhaust ports have been closed.

In the construction shown in Figures 1, 4 and 5 the admission ports 9 and 10 are arranged tangentially while the admission ports 5, 7 are disposed truly radially; the ports 9 being formed so as to be closed after the exhaust ports 6 during 80 the compression stroke, while the ports 10 are closed substantially simultaneously with the exhaust ports 6.

In the construction shown in Figures 2, 6 and 7, on the other hand, the ports 9 and 7 enter the cylinder truly radially while the ports 10 enter the cylinder tangentially so that the air enters therethrough in the direction of the arrows indicated at 11 in Figure 2 and at 12 in Figure 6. 85 In this way a rapid scavenging of the space immediately above the piston face is ensured when the piston is at its lower dead centre.

The various port openings are best described with respect to their locations in the cylinder wall, by defining certain segments of the cylinder in which the ports are placed. If two parallel planes are passed through the cylinder at right angles to the principal axis thereof, a cylinder segment is obtained between the planes. By passing one of such planes to embrace all the lower edges of the admission ports 5 and 7 and another of such planes to embrace all of the top edges of ports 5 and 7, a cylindrical segment is defined in which the ports reside. Similarly, a second cylinder segment is defined by passing

such planes to embrace the top and the bottom edges of the admission ports 9 and 10. This second segment defines the location of the ports 9 and 10. The ports 9 and 10 are located above the ports 5 and 7, in other words, they are closer to the cylinder head than ports 5 and 7. It is, therefore, apparent that a substantial length of cylinder wall exists between these two groups of admission ports.

10 In the construction shown in Figures 3, 8 and 9, the ports 9 and 10 are all disposed tangentially while the ports 5 and 7 are disposed truly radially, all the ports 9 and 10 in this construction being so formed that they are closed during the 15 compression stroke after the exhaust ports are closed. The direction of the air entering through the ports 9 and 10 is indicated by the arrows 13 and 14 in Figure 3 and by the arrow 15 in Figure 8, while the path of this air is also shown 20 by the chain line in Figure 3. This air forms what may be regarded as a gyrating wall enclosing the air admitted through the lower set of admission ports 5 and 7, thus tending to prevent the air entering through the ports 5 from flowing directly across the cylinder and out through the 25 exhaust ports 6.

It will be seen that with a construction according to the present invention the air entering the

cylinder tangentially acts to cause the air entering radially to follow a prescribed path and thus tends to prevent this air passing directly out through the exhaust ports without performing useful scavenging work.

Further, the tangential entry of the air through some of the admission ports has the advantage that by directing this air at a suitable angle towards the cylinder head a rotating layer of air in contact with the whole surface of the cylinder can be formed so that the rotation of the air and the kinetic energy contained therein is maintained during the compression stroke and assists the atomizing of the fuel.

I claim:

In a two-stroke internal combustion engine the combination comprising a cylinder, a reciprocal piston within said cylinder, a plurality of radial admission ports converging toward the center of the cylinder within a segment of the cylinder, a plurality of tangentially disposed admission ports within a second segment of the cylinder, the second segment disposed above and apart from said first mentioned segment, and a plurality of exhaust ports, portions of which lie within each of said cylinder segments.
